The ornamental design for an electronic device adapter, as shown and described.

DESCRIPTION

FIG. 1 is a first perspective view of a first embodiment of an electronic device adapter, taken from above;

FIG. 2 is a second perspective view of the first embodiment of the electronic device adapter of FIG. 1, taken from below;

FIG. 3 is a front view of the first embodiment of the electronic device adapter of FIG. 1;

FIG. 4 is a back view of the first embodiment of the electronic device adapter of FIG. 1;

FIG. 5 is a right-side view of the first embodiment of the electronic device adapter of FIG. 1;

FIG. 6 is a left-side view of the first embodiment of the electronic device adapter of FIG. 1;

FIG. 7 is a top view of the first embodiment of the electronic device adapter of FIG. 1;

FIG. 8 is a bottom view of the first embodiment of the electronic device adapter of FIG. 1;

FIG. 9 is a first perspective view of a second embodiment of an electronic device adapter, taken from above;

FIG. 10 is a second perspective view of the second embodiment of the electronic device adapter of FIG. 9, taken from below;

FIG. 11 is a front view of the second embodiment of the electronic device adapter of FIG. 9;

FIG. 12 is a back view of the second embodiment of the electronic device adapter of FIG. 9;

FIG. 13 is a right-side view of the second embodiment of the electronic device adapter of FIG. 9;

FIG. 14 is a left-side view of the second embodiment of the electronic device adapter of FIG. 9;

FIG. 15 is a top view of the second embodiment of the electronic device adapter of FIG. 9; and,

FIG. 16 is a bottom view of the second embodiment of the electronic device adapter of FIG. 9.
